UNITED STATES PATENT OFFICE

GEORGE TANNER, OF SANDPOINT, IDAHO

SAWMILL SETWORK

Application filed March 28, 1929. Serial No. 350,646.

My present invention relates to improvements in saw mill set works as applied to the transversely reciprocable knees of the reciprocable saw mill carriage employed in sawing logs. The primary object of the invention is to improve the construction and operation of the knees and related parts for the purpose of eliminating excess friction and consequent binding and to insure a smooth action of the moving parts; to provide resilient mechanical means and also pneumatic means for absorbing and cushioning shocks due to the starting and stopping of reciprocating parts; to insure greater accuracy in cutting the log together with economy in time and labor; to provide means for taking up or compensating for wear especially in the dogging mechanism; and thus increase the efficiency of the operating parts for the production of a better grade of material.

As is well known in the trade, the backward and forward movement of the reciprocating carriage tends to cause the topheavy knees to lean in the direction opposite to that of the travel of the carriage, and this leaning or tilting produces excessive friction and consequent binding of parts. By the utilization of the devices of my invention, anti-friction means are employed for eliminating the binding of the transversely movable knees, thus facilitating the setting and receding of the knees.

A pneumatic mechanism is employed for cushioning the movement of the knees in their setting and receding movements to eliminate lost motion or slack movements in the knees, the rack and pinion mechanism and the tapering devices.

A resilient mechanical cushioning device is utilized in connection with the dogging mechanism; and in connection with the dogs I utilize devices for taking up wear to insure at all times a compact arrangement of the operating parts whereby the log is rigidly held in position in order that the log may be sawed with accuracy.

The invention consists in certain novel combinations and arrangement of parts as will hereinafter be more fully set forth and claimed. In the accompanying drawings I

have illustrated one complete example of the physical embodiment of my invention in connection with a well known type of knees, wherein the parts are combined and arranged according to the best mode I have thus far devised for the practical application of the principles of my invention.

Figure 1 is a view in side elevation of one of the knees projected to extreme forward position transversely of the saw mill carriage, which is shown in end elevation, showing the dogging mechanism in dotted lines, and indicating the position of the saw.

Figure 2 is an enlarged, vertical, sectional, detail view of a resilient bumper for the dogging mechanism, and Figure 3 is a sectional view at line 3—3 of Figure 2.

Figure 4 is a detail side view at the front end of the backing off or receding cylinder showing the piston stem connected with the knee, and Figure 5 is a top plan view of the parts in Fig. 4. Figure 6 is a longitudinal sectional view on the backing off or receding cylinder and piston therein.

Figure 7 is an enlarged view in side elevation of one of the anti-friction carriages for the knee, one of the carriages being located at each side of the knee.

Figure 8 is a vertical, transverse sectional view at line 8—8 of Figure 7 showing also, at the left, the carriage-pin and its roller in the taper slot of the knee.

Figure 9 is an enlarged detail elevation at the front of a knee showing the dogging mechanism, and Figure 10 is a face view of the mechanism as seen from the right in Figure 9 with parts omitted for convenience of illustration. Figure 11 is a cross sectional view at line 11—11 of Figure 9.

Figure 12 is a face view at the front lower portion of the knee.

Figures 13 and 14 are enlarged plan views of wear-plates used with the lower dog for guiding the movement of the latter and to compensate for or take up wear of the parts.

Figure 15 is a vertical longitudinal section through the knee of Figure 1 showing the dog holder and related parts.

Figure 16 is a face view of the dog holder of Figure 15.

Figure 17 is a perspective view, from the rear, of the dog holder, with operating parts omitted.

In order that the general arrangement of parts may be readily understood I have shown in Figure 1 a pair of rails 1, 1, over which the wheels 2, 2, of the carriage 3 roll, as the carriage reciprocates in the usual manner. The saw is indicated at 4, and the logs 10 are carried on the transversely disposed head-blocks 5, a plurality of which are used at suitable intervals along the saw mill carriage.

In Figure 1 the usual rack 6, pin 7, operating shaft 8, and pinion 9 are indicated, for use in advancing and receding the several knees indicated as a whole by the number 10, it being understood that the knees are reciprocated transversely of the saw mill carriage between the cutting or sawing operations as required.

As the knee reciprocates, the rack rolls on the pinion and the knee, under ordinary conditions, slides across the top of the head block. To relieve the excessive friction on these parts, and to prevent the knee from tilting (as the saw mill carriage moves) and consequent binding, I utilize pin 7, and slots 11 in the opposite side-walls of the knee, for anti-friction rollers 12.

The carriage pins 7, at opposite ends project through the slotted walls of the knees, and at each end of each carriage pin a carriage or housing 13 is provided for the support of the knee and to facilitate its forward and receding movements across the knee block.

The carriage at each side of the knee is of inverted U-shape in cross section, and each carriage is provided at its longitudinal center with a vertically disposed bearing slot 14 for the end of the carriage pin 7. By means of a pair of spaced U-bolts 15 that partly encircle the pin, nuts 16 on the upper threaded ends of the U-bolts and pads or plates 17 on the tops of the carriages, the carriages support the pin 7, and it will be apparent that the vertical slots 14 of the carriage permit adjustment of the pin ends in the carriages. At ends of each carriage a roller as 18 is journaled by the use of journal pins 19 in the walls of the carriage, and these rollers travel over the complementary, spaced track plates 20 on the top of the head block. The carriages at the sides of the knee are thus adapted to be adjusted with relation to the knee and track plates so that the rollers 12 in the taper slots and the rollers 18 on the track plates will engage their frictional surfaces in such manner as to retain the knee against lateral movement or wobbling, and yet permit the required freedom of rolling movement on the part of the knee as it is advanced and receded with relation to the log or the head block.

The carriage pin 7 also has pivotally connected therewith the side links 21 that extend

rearwardly to the rocker arms 22 of the usual taper set cylinder 23.

The usual backing off or receding mechanism that pulls the knee to the right in Figure 1, and normally holds the knee in receded position, as well as performing the usual functions of a pneumatic shock absorber, is indicated by the compressed air or steam cylinder 24 that is rigidly attached at 25 to the head block. Within the cylinder, the piston 26 is adapted to reciprocate, and its stem 27 projects forward alongside the knee, and is connected to the latter by means of a coupling head 28 on the coupling sleeve or collar 29 that is clamped on the horizontally projecting hub 30 of the knee, by means of bolts 31 as seen in Figures 4 and 5. Compressed air is supplied to the cylinder near its front end at 32, and near the rear end of the cylinder an inwardly opening, automatic check valve 33 is provided. At 34 a pressure relief valve is connected at the rear end of the cylinder. The admission of air at the inlet valve 32 is under control of the man who rides the saw mill carriage, and when applied, the air pressure pulls or recedes the knee to the right in Figure 1, thus backing it off from the log, or from the position of Figure 1, in connection with the rack and pinion mechanism. As the sawing proceeds and the log is frequently turned, the backing off mechanism provides a pneumatic cushion to absorb shocks from the starting and stopping of the movements, and also to stabilize the knee in its different positions.

The dogging mechanism carried within the knee includes an upper dog 35 and a lower dog 36, the latter to be used on logs of smaller diameter than those for which the upper dog is adapted.

The dogs are carried on a dog holder 37 that is vertically slidable within the knee on the guide bar 37' and they are adapted to be projected through the slot in the front of the knee between the two face plates 38.

At the rear side of its upper end the dog holder is provided with a bracket-collar 39 that is fitted over and fastened on the upper end of the plunger stem 40 which extends into the pneumatic cylinder 41 of the dogging mechanism. Within the cylinder suitable actuating means are employed under air control, and as shown in Figure 15 the cylinder 41 is supported on a cushioned bracket 42 that is pivoted to the guide bar or dog bar 37', and it is cushioned by its bolt 79 and spring 80 on the bolt, the head of the bolt sliding on the plate 81 of the knee. The dog holder is raised and lowered to operate the dogs, and anti-friction rollers 43 are carried by the holder for frictional, rolling contact with the rear edges of the face plates 38 of the knee.

As best seen in Figure 9 the upper dog 35

is supported in the holder by the pivot pin 44, and the dog has a slot 45 which permits a slight relative movement of the dog on its pivot when the dog is forced into the log. 5 Near the upper end of the pivoted dog a spring 46 is attached and the other end of this spring is anchored to the holder at 47. Above the spring on the extreme end of the dog is provided a cam shaped stop 48 which 10 acts with a cam shaped stop 49 that is fixed on the holder. The spring normally holds the point of the dog extended with the stops, and it will be apparent that as the slotted dog moves upwardly on its pivot pin as the 15 dog engages the log, the action of the cam head and cam causes the point of the dog to swing inwardly toward the knee, thus swinging or pulling the log inward and tight against the face plates of the knee. In this 20 manner the log is rigidly held against movement and in close frictional contact with the knee so that the saw may make an accurate cut in the log. When the dog is released from the log, the spring is free to pull the dog down 25 to normal position in Figure 9.

The lower dog 36 is also adapted to draw or turn inwardly the log toward and against the knee, and its hooked point 36' as it penetrates the log, coacts with the upward "give" 30 of the curved dog, for this purpose. The curved or arc-shaped dog 36 slides between and is guided by wear blocks, three of which are designated as 50, and the fourth as 53, and the four blocks are arranged in pairs at the 35 opposite curved sides of the dog, within the dog holder. The blocks 50 which have angular sides are here shown as rectangular, but other shapes may be used, and each block has an opening 51 eccentric to or off 40 set from the center of the block in order that various edges are located at differing distances from the opening. The openings in the blocks are slipped over pins 52 of the holder, spaced at opposite sides of the dog. 45 Thus as the edges of the dogs, or the edges of the guide blocks, wear, the blocks may be removed and replaced with a fresh guide edge for contact with the curved edges of the dog, and these fresh edges compensate for or take 50 up the wear, and maintain the dogs in proper condition to prevent loose movement or lateral "give" as they slide in their blocks. At the concave edge of the dog a heart-shaped block 53 is located, and its offset or eccentric hole 54 fits the block over the pin 55 in the holder. This heartshaped block with convex curved faces complementary to the concave face of the dog, may also be turned over on its pin to bring a fresh bearing edge against the dog 55 to take up wear between the dog and block. A head or stop 56 is provided at the top of the dog to overhang one of the guide blocks 50 and limit the downward movement of the dog. 60 A guide rod 57 is hinged to the lower dog

at 58, and extends upwardly in the holder through a guide bushing 59, and a spring 60 coiled about the guide rod is interposed between the hinge joint and the guide bushing to normally hold the dog in lowered position with its stop head 56 in contact with one of the guide blocks, and to return the dog to this position after it has been released from the log. As the pointed hook 36' engages the log the dog is forced upwardly against the compression of the spring, and the retracting movement of the arc-shaped dog between its guide blocks causes the hooked end to hold the log against the face of the knee. 70

The dog holder and guide bar 37' are held against loose lateral movement, by means of an air cushion, and also by a spring which includes a resilient blade 61 that frictionally engages the edge of the bracket 42, and is adjustable to take up wear on the operating parts of the dog holder and dog bar caused by the operation of the dogging mechanism. As seen in Figures 2 and 3 the spring cushion device is located at the back of the knee, and is suspended from a portion of the knee as a support by means of the upper hooked end 62 that overhangs the knee-wall. The hooked end is slotted at 63 and lies flat against the knee, and stud bolt 64 threaded into the knee, extends through the slot of the cushion, with lock nuts 65 on the bolt for clamping the slotted bent end of the cushion rigidly against the knee. The cushion may be vertically adjusted when the lock nuts 65 are loosened, and this adjustment may be secured by the use of a set bolt 66 in the top of the cushion blade, which bolt bears down on the top of the knee-wall and is secured by lock nut 67. At its lower free end the resilient blade of the cushion is provided with a pair of side links 68 that are pivotally connected with the cushion by means of the bolt 69 and the clamp nuts 70. By means of the pivot bolt 71b the upper rear ends of these links are hung on the knee walls as a support, and it will be apparent that the resilient cushion is thus adapted to be adjusted for frictional contact with the bracket to hold the latter against any lost motion and yet permit it to 80 "give" slightly under strains. 90

The dog holder is also held against loose movement, laterally by means of the combined air cushion in the cylinder 71a and its piston rod 71, and the bumper 61 shown in Figures 2 and 3. The cylinder 71a is supported in a frame 78 on the outside of the knee wall and rod 71 is connected to the long arm of a bell crank lever 72, which is pivoted at 73 on the knee 10, the short arm of the lever being pivoted to the dog holder at 74. A complementary bell crank lever 72a is pivoted on the knee and pivotally connected with the lower portion of the dog holder, and a connecting rod 75 pivotally connects the two 95 100 105 110 115 120 125 130

A head or stop 56 is provided at the top of the dog to overhang one of the guide blocks 50 and limit the downward movement of the dog. 60 A guide rod 57 is hinged to the lower dog

bell cranks. The air cushion is obtained by adjusting the parts as follows: Assuming that the points of the dogs (35 and 36) are to be set so that they will recede toward and to within $\frac{1}{2}$ inch of the face of the knee with a cushioned stop to prevent wear and tear on the parts, the nut 76 on the rod 71 is first loosened, and the rod pushed downwardly until its piston in cylinder 71a contacts with the bottom of the cylinder. The threaded end of the piston rod is then turned in the pivot-shackle 77 of the bell crank 72 until, through the action of the bell cranks, the dog holder advances the points of the dogs to about $\frac{1}{4}$ inch beyond the face of the plate 38. The lock nut 76 on the threaded end of the piston rod is then tightened on the shackle.

The adjustment of the piston in cylinder 71a provides a space in the cylinder below its piston so that after the dogs have been projected to engage a log and are pulling the log toward plate 38 and the part 42 engages the bumper 61, the latter resists further movement, but, as the impact is liable to break the arms 68, the air cushion in the cylinder 71a functions to cushion the impact and prevent undue strain on the links 68.

Various parts of the set works are illustrated for convenience of illustration and description, and it will be understood that the operating parts of the mechanisms are under control of the setter or man riding on the carriage of the saw mill. The knee is advanced and receded through the action of the rack 6 and pinion 9 on the shaft 8, the latter being controlled in its movements by pneumatically operating parts not shown. As the reciprocating movements of the knee are usually abrupt, these movements are cushioned and the shocks absorbed by the pneumatically operating receding mechanism including the stem 27, cylinder 24 and other parts.

The knees are receded from the position in Figure 1 in order that the log may be placed on the carriage, and the knees are then advanced to the log, after which the dogging mechanism, under control of the setter, is operated to engage one or the other of the two dogs with the log. The log is manipulated by a device termed a "nigger" and is thereby clamped against the knees and held in rigid position by the dogging mechanism while the cutting operations are proceeding.

Having thus fully described my invention, what I claim as new and desire to secure by Letters Patent is:—

1. The combination with a reciprocable knee having spaced slotted side walls, operating means therefor, and a support, a pin disposed transversely of the knee, and rollers on said pin movable in the slots of the knee, of a carriage at each side of the knee for supporting said pin, and anti-friction devices on the carriage.

2. The combination with a reciprocable knee having slots at its opposite sides, a transversely arranged pin having rollers thereon in the slots, and operating means for the knee, of a carriage supporting the opposite ends of the pin exterior of the knee, a support, and anti-friction rollers on the carriages adapted to travel on the support. 70

3. The combination with a reciprocable knee having spaced walls and slots therein, a pin having rollers in said slots and operating mechanism connected with the pin, of a support, carriages supporting the opposite ends of said pin and bearing rollers on the carriages adapted to travel on the support, 80 and means for adjusting the carriages relatively to the pin for equalizing the load of the knee on the carriages. 75

4. The combination with a reciprocable knee, operating means therefor, a pin disposed transversely of the knee, and a support, of a pair of carriages movable on the support and adapted to support the ends of the pin, and means for adjusting the carriages relatively to the pin for equalizing the load of the knee on the carriages. 85

5. The combination with a reciprocable knee having slotted side walls, a transversely disposed pin mounted in said walls, of a carriage having a bearing slot for the pin, and means for adjusting and supporting the pin in the slot. 95

6. The combination with a reciprocable knee having slotted side walls and a pin mounted in said walls, of a pair of carriages each having a vertical bearing slot for the pin, suspending means on the carriage for supporting the pin, means for adjusting the suspending means and means for retaining the suspending means in adjusted position. 100

7. The combination with a dog-holder and a knee, of a resilient cushion for the holder comprising a blade located to the rear of the dog-holder for contact therewith, means for moving the dog-holder toward and from the blade, means for suspending the blade on the knee; and means for holding the blade in suspended position. 105

8. The combination with a dog-holder and knee, of a resilient knee for contact with the holder, adjustable means for supporting the bumper from the knee and means for fastening the bumper in adjusted position, and supporting links pivoted to the free end of the bumper and loosely mounted on the knee to permit play upon engagement of the dog-holder with the cushion. 110

In testimony whereof I affix my signature.
GEORGE TANNER.
